UNITED STATES PATENT OFFICE.

ARTHUR T. KUEHNER, OF ELKRIDGE, MARYLAND.

LOCOMOTIVE SMOKE-BOX FRONT.

Application filed October 4, 1919. Serial No. 328,562.

To all whom it may concern:

Be it known that I, ARTHUR T. KUEHNER, a citizen of the United States, residing at Elkridge, in the county of Howard and 5 State of Maryland, have invented certain new and useful Improvements in Locomotive Smoke-Box Fronts, of which the following is a specification.

This invention relates to an improved locomotive smoke box front and has as one of 10 its principal objects to provide a construction wherein the smoke box front may be readily removed, removal of the front being, as is well known, necessary in order that 15 any superheater units, the superheater header, or steam pipes may be removed from the locomotive.

The invention has as a further object to 20 provide an improved hinge mounting for the front so that, in removing the front, it may simply be swung to one side.

A further object of the invention in this connection is to provide a hinge mounting of 25 such nature that the front may be swung clear of any obstructions upon the forward end portion of the locomotive such as bumper knees, and on the Mallett type of locomotive, the steam chest exhaust pipes, hand rails, headlight, and sand boxes.

30 A still further object of the invention is to provide a hinge mounting wherein the front will be hingedly supported at diametric points for effectually sustaining the weight of the front and eliminating sagging 35 as well as the extreme stress upon the front and the hinge mounting which would otherwise occur.

And the invention has as a still further 40 object to provide a construction wherein the means employed for normally securing the smoke box front in position will also serve to reinforce the front at its peripheral margin to prevent warping thereof.

Other and incidental objects will appear 45 hereinafter.

In the drawings:

Figure 1 is a side elevation showing a locomotive of conventional type equipped with my improved smoke box front.

50 Figure 2 is a plan view illustrating the front applied.

Figure 3 is an elevation of the front applied.

55 Figure 4 is a detail perspective view showing the uppermost of the hinge arms employed, and

Figure 5 is a perspective view showing one of the clamps employed for normally securing the front in position.

Referring now more particularly to the drawings, I have shown my improved smoke box front in connection with a conventional type of locomotive having the usual smoke box 10. The smoke box front is indicated at 11, this front being provided with the usual door 12 and seating flat at its peripheral margin, as is usual, against the customary smoke box ring at the front of the smoke box. In this connection it may be observed that in any instance where the present invention is applied to a locomotive already in use, no change need be made in the door 12. However, where the invention is incorporated in a locomotive at the time of its construction, the door may, owing to the facility with which the smoke box front may be removed as shall presently appear, be much smaller than is now commonly practiced.

Mounted upon the peripheral margin of 80 the front 11 at its outer face is a series of segmental reinforcing plates, the major number of which are, for convenience, indicated at 13, while the pair of plates disposed diametrically opposite each other at 85 the upper and lower sides of the front respectively are indicated at 14, the plates abutting at their ends and forming a reinforcing ring at the outer margin of the front. As will be seen, these plates will 90 serve to stiffen the margin of the front and will materially tend to prevent warping thereof such as is now experienced in connection with smoke box fronts as commonly constructed. The plates may be riveted or 95 otherwise secured in position and the usual bolt holes formed in the margin of the front therefor may be employed to receive said rivets. The reinforcing plates may accordingly be applied without structural change 100 in the front. Upstanding from the outer edges of the plates 13 at points substantially midway between the ends thereof are pairs of spaced lugs 15. Secured about the forward margin of the smoke box at its outer side is a series of spaced anchoring plates 16 riveted or otherwise secured to the smoke box wall and hingedly mounted upon these plates at their forward ends are clamping bolts 17 each adapted to freely engage between a pair of the lugs 15. Threaded upon

105

110

said bolts at their outer ends are nuts 18. Thus, as will be clear, these nuts may be tightened for firmly clamping the smoke box front in position while, by simply loosening 5 the nuts and swinging the clamping bolts 17 rearwardly, the front may be freed.

It is now to be observed that the plates 14 are somewhat longer than the plates 13, the plates 14 being formed, as shall now appear, to provide hinge plates. Formed on these plates at their rear sides are lugs 19. Suitably secured to the forward end portion of the smoke box adjacent its upper side is a hinge plate 20 provided, as particularly shown in Figure 4 of the drawings, with a vertical socket 21 and similarly secured to the smoke box adjacent its lower side is a hinge plate 22 offset at its outer end portion away from the smoke box wall. 10 In practice, it is intended that each locomotive shall be equipped with a pair of hinge plates 20 and 22 and I shall now proceed to describe the hinge arms employed to coact with these plates whereby the smoke 15 box front may, after having been released, be swung to one side. However, it should be explained in this connection that since it is practicable to remove the smoke box front only when the locomotive is at a proper shop or terminal, it accordingly becomes unnecessary to permanently mount the hinge arms. It is, therefore, intended that one or more pairs of the hinge arms shall be kept at each shop or terminal and 20 applied when the actual operation of removing the smoke box front of a locomotive is undertaken.

The hinge arms are indicated at 23 and 24 respectively, the arms being shown, in 25 the present instance, applied. These arms are respectively formed of long and short inner and outer pivotally connected sections. The longer section of the upper arm 23 is provided at its inner end with a trunnion 25 adapted to removably engage within the socket 21 of the plate 20. On the other hand, the longer section of the arm 24 is provided at its inner end with a yoke 25' to freely embrace the outer end of the hinge 30 plate 22 to which it is pivotally connected by a pivot bolt 26. Formed on the shorter sections of the arms at their outer ends are yokes 27 adapted to freely embrace the hinge lugs 19 of the plates 14 and pivotally connecting these yokes with said lugs are pivot bolts 28. As will thus be seen the hinge arms may be readily applied. When 35 so applied, the smoke box front may, in the manner previously indicated, be released, when the hinge arms will then support the front. Consequently, the front may be readily swung to one side and, by pivoting the outer sections of the hinge arms upon the inner sections thereof, may be so moved 40 as to clear all obstructions such as bumper

knees, hand rails, or the like, at the forward end portion of the locomotive, it being possible to not only swing the front horizontally but also turn the front about the vertical axis of the pivot bolts 28 as well as the vertical axis of the pivotal connection between the inner and outer sections of the arms. In this connection, particular attention is directed to the fact that since the outer sections of the arms are mounted to swing upon the inner sections thereof while the front may also be rotated upon the outer sections, it becomes possible to move the front away from the smoke box for a certain distance in a straight line when the front may then be swung laterally. Furthermore, since the hinge plates 14 are disposed diametrically opposite each other, the hinge arms will support the smoke box front medially thereof. Sagging such as would occur were the front to be hinged at one side, will accordingly be eliminated while the stress of the front will be more equally distributed between the hinge arms. Extending rearwardly from the uppermost of the hinge plates 14 is an arcuate flange 29 engaging over the forward margin of the smoke box wall at its upper side. This flange is designed to support the smoke box front should the bolts 17 be unintentionally released before the hinge arms are applied so as to prevent accidental dropping of the front. It will accordingly be seen that I provide a particularly effective construction for the purpose set forth while the smoke box front may be readily employed in connection with substantially any conventional type of locomotive.

Having thus described the invention, what is claimed as new is:

1. The combination with a locomotive, and a smoke box front closing the smoke box of the locomotive, of a series of mating plates extending around the peripheral margin of the front and forming a reinforcing ring thereon, means coacting with certain of said plates for detachably securing the front in position, and means adapted to extend between the smoke box and certain other oppositely disposed plates for pivotally supporting the front whereby the front may be swung to one side.

2. The combination with a locomotive, and a smoke box front closing the smoke box of the locomotive, of reinforcing plates carried by the peripheral margin of the front and provided with lugs, plates secured to the smoke box, clamping bolts pivoted upon the latter plates and coacting with said lugs for detachably securing the front in position, and means adapted to extend between the smoke box and the front for pivotally supporting the front whereby the front may be swung to one side.

3. The combination with a locomotive

smoke box, of a front for the smoke box movable to open position in substantial parallelism with the front end of the smoke box, fastening means for the front, a mounting carried by the smoke box, a mounting carried by the front, and an arm engageable with said mountings for suspending the front for bodily movement away from the smoke box when said fastening means are released but normally detached from said mountings whereby a single arm may function as a master fitting for engagement with corresponding mountings of several locomotives.

4. The combination with a locomotive smoke box, of a front movable to open position in substantial parallelism with the front end of the smoke box, fastening means for the front, and suspension means extending between the smoke box and front at the rear of the front for sustaining the front when said fastening means are released for bodily movement away from the smoke box

as well as rotation about a vertical axis lying in a plane at the rear of the front whereby 25 the front may be moved to a position having its inner side lying near to a side of the smoke box substantially parallel to the axis of the smoke box.

5. The combination with a locomotive 30 smoke box, of a front for the smoke box movable to open position in substantial parallelism with the front end of the smoke box, fastening means for the front, a socket mounted upon the smoke box, a plate mounted upon the front, an arm extending between said socket and plate and formed of pivotally connected sections one having a trunnion rotatably fitting in said socket, and means pivotally connecting another of said 40 sections with said plate, the arm being disposed to suspend the front for bodily movement away from the smoke box when said fastening means are released.

In testimony whereof I affix my signature. 45
ARTHUR T. KUEHNER. [L.S.]
